UNITED STATES PATENT OFFICE.

JOHN R. WILLIAMSON, OF WASHINGTON, DISTRICT OF COLUMBIA.

STIRRUP.

Specification of Letters Patent No. 30,369, dated October 9, 1860.

To all whom it may concern:

Be it known that I, JOHN R. WILLIAMSON, of the city of Washington, in the District of Columbia, have invented new and useful 5 Improvements in Stirrups for Riding-Saddles, called an "Oscillating Step and Anti-friction Stirrup;" and the following is a clear and exact description of the same, reference being had to the accompanying drawings, making a part of this specification, in which—

Figure 1, represents an upright side view. Fig. 2, shows an edge view, with the position of the step changed, (in dotted lines.) 15 My invention consists in making stirrups with the step movable on pivots, so that it can vary to any angle or turn over and change sides in the bow, the rods or support for the foot being friction rollers, as also the 20 sides of the bow, as high as is necessary for the sides of the foot to bear against, thereby making it an anti-friction stirrup.

To enable others skilled in the art to make and use my invention, I will describe it, referring to the drawings and the letters marked thereon.

The bow (A, A,) may be made of iron or steel rods, bent in any required form and of any size desired, the lower ends having eyes 30 (a, a,) in which to secure the step (B.) On each side of the bow (A, A,) are rollers (b, b,) one or more in number, which may be made of metal tube or of any equivalent material to prevent friction. The step or foot 35 piece (B) is made by having two end pieces (C, C,) which are pivoted to the eyes (a, a,) by set screws (e, e,) fitted into them, they

being connected together by two or more rods (D, D,) which of themselves may form friction rollers, or they may have tubes of 40 metal or any equivalent covering that will be antifriction, so as to liberate the foot, the step (B,) being pivoted on the center of the pieces (C, C,) so as to balance, and will 45 vibrate or turn either way, and will take any inclination to suit the position of the foot, while the rollers (b, b,) on the sides of the bow (A, A,) prevent wear to the shoe and serve to liberate the foot, so that it cannot hang, by being turned or cramped in the 50 stirrup should the rider be unhorsed. It is a lamentable fact that very many serious accidents occur by persons being thrown from the saddle and the foot being caught and held, by the rigidity and roughness of 55 the stirrup.

By my peculiar construction of the movable step and the arrangement of the friction rollers on both bottom and sides for the foot to bear against it becomes a most perfect anti-friction stirrup.

Having thus fully described my invention, what I claim as new, and desire to secure by Letters Patent is—

The rotating and oscillating step having 65 friction rollers or their equivalents on both the step and sides of the bow, constructed and arranged in the manner and for the purposes herein specified.

JOHN R. WILLIAMSON.
